PHILIP G. RUST, OF WILMINGTON, DELAWARE, ASSIGNOR TO THE VISCOSE COMPANY,
OF MARCUS HOOK, DELAWARE, A CORPORATION OF PENNSYLVANIA

MEANS FOR TREATING YARN

Application filed August 2, 1928. Serial No. 297,075.

This invention was primarily made in connection with the manufacture of artificial silk or rayon by the wet method, the main object being to obtain a simple and efficient method of and means for freeing the thread in the process of manufacture from the excess of chemicals used in forming the thread. This particular form of washing or "quenching", as it is technically called in the factory, takes place as the thread or yarn passes on its way from the forming bath to the spinning box.

There are various ways in which threads or yarns may be so washed or quenched. For example, one way would be to run in a trough of water the godet or a reel on which the yarns are wound, but that is open to the objection that that will require several extra thread guides, and practice has shown that with that arrangement, considerable difficulty is experienced in starting the operation.

Another possible method of washing or quenching would consist in dripping the washing liquid onto the top of the revolving godet, but that method is not satisfactory because of the resulting spray, and experience has demonstrated that the washing so carried on is not uniform.

I have found that the thread or yarn can be easily but efficiently washed by causing it to pass around a fixed guide, and subjecting the thread there to the action of a stream of water or other liquid. For this purpose I use a hollow guide, through which the washing liquid is supplied and allowed to flow out of an opening in the guide and to flood the thread or yarn as it passes about the guide.

In the accompanying drawings I have shown how my invention may be applied and carried out in connection with the spinning of artificial silk or rayon by the wet process, but my invention may be applied in other connections and operations, as for example in reeling, winding or sizing processes, or generally in any operation requiring the exposure of a thread to a liquid.

In the drawings:

Fig. 1 is a side elevation (with part of the framework in section) of the combination

of a revolving godet with a form of my improved thread guide;

Fig. 2 is a corresponding face view of the same parts;

Fig. 3 is a plan view of the thread guide; 55

Figs. 4 and 5 are plan and sectional views of a modified form of thread guide.

In Figs. 1 and 2, G represents a godet mounted to revolve in a bearing g carried by the fixed frame F of a machine for forming and spinning artificial silk or rayon by the wet process. At X I have indicated the thread coming from the forming bath and passing in three turns, 1, 2, 3, around the godet and passing on its way at Y towards the spinning box, not shown. The thread on its way to the first turn 1 is shown as guided by one of the fingers of a fork H, and then on its way to the second turn 2 is shown as guided by another part of the same fork. On leaving the second turn 2, the thread is passed around a notch a on the underside of what I term a flooding thread guide A, which in this instance is shown as mounted in a position below the godet G. There the thread is washed or quenched as I will describe, and thence the thread is shown as passing once more around the godet at 3 and then down at Y towards the spinning box below. 75

The flooding thread guide A is made hollow with means for admitting water or other liquid to the interior, and near its outer end there is provided an outlet a' for the liquid in such a position that the water flowing out of this outlet will flood the outside of the thread guide about the groove a and so thoroughly wash the thread as it passes about that groove. In the drawings I have shown this outlet a' as on the upper side of the tube of the guide near the outer end of the tube which is closed, and the tube itself is so mounted in the frame F as to stand in a tilted position with its outer end higher than its inner end. Consequently the water or other washing liquid will flow down the outside of the tube in a stream as indicated in Fig. 1, thoroughly flooding the thread on the way. 90

Any suitable arrangements may be made for supplying a stream of washing fluid to each guide A, which, by the way, may be made

conveniently of glass or porcelain or even of metal or a composition which will not be injured by, and will not injure, the chemicals coming in contact with it.

5 In the form illustrated in Figs. 1 to 3, I have shown the tube A as provided with an inlet branch b to which flexible hose may be connected. In this case the back end of the tube will be closed.

10 In the form shown in Figs. 4 and 5, the guide A' is open at the back end to admit there the supply of washing fluid.

Although I have shown the flooding thread guide as arranged under the godet it may be 15 arranged in any other convenient position, and in connection with any other suitable wheel, reel or bobbin.

I regard it as a surprising discovery to find 20 that such a short contact of the thread with the liquid produces such an efficient washing and cleansing effect. I attribute this efficiency largely to the fact that the thread as it passes around the thread guide is under sufficient tension to flatten there, thus exposing 25 the individual filaments more completely to the action of the stream of liquid.

I claim as my invention—

1. A tubular thread guide with an outlet 30 for liquid on its upper side, and a thread depression on its under side adapted to contact with the thread and to be flooded by flowing liquid.

2. A tubular thread guide adapted to be mounted in a tilted position with outer end 35 up, said outer end being provided with an outlet for the liquid, and the under side of the tube being provided with a thread depression towards the inner end of the guide.

In testimony whereof I have signed my 40 name to this specification.

PHILIP G. RUST.
